(57) **CLAIM**

The ornamental design for a billboard light fixture reflector, as shown and described.

DESCRIPTION

FIG. 1 is a perspective view of the billboard light fixture reflector according to my new design;

FIG. 2 is another perspective view of the reflector;
FIG. 3 is a right side view thereof, the left side being a mirror image;

FIG. 4 is a front view thereof;

FIG. 5 is a rear view thereof;

FIG. 6 is a top view thereof; and,

FIG. 7 is a bottom view thereof.

The broken lines in the drawings show environmental structure and form no part of the claimed design.
